UNITED STATES PATENT OFFICE.

LEMUEL MELLETT AND JEROME PRINCE, OF MILFORD, ASSIGNEES TO
SAID LEMUEL MELLETT, AND GEORGE REED, OF FITCHBURG, MASSA-
CHUSETTS.

ELECTRIC ORE-INDICATOR.

SPECIFICATION forming part of Letters Patent No. 367,541, dated August 2, 1887.

Application filed March 24, 1886. Serial No. 196,353. (No model.)

To all whom it may concern:

- Be it known that we, LEMUEL MELLETT and JEROME PRINCE, both of Milford, county of Worcester and State of Massachusetts, have 5 invented an Improvement in Electrical Indicators, of which the following description, in connection with the accompanying drawings, is a specification, like letters on the drawings representing like parts.
- 10 This invention has for its object to provide apparatus by which the presence of mineral ores or metallic substances either on or below the surface of the earth or under water may be indicated.
- 15 Our invention is especially adapted to be used in locating veins or deposits of mineral ores in the earth and also for the detection of metallic substances under water.
- 20 The particular features of our invention will be pointed out in the claims at the end of this specification.
- 25 Figure 1 is a top view of a case containing the apparatus by which to practice our invention. Fig. 2 is a vertical section of Fig. 1 in the line x x , through the indicator or galvanometer; Fig. 3, a longitudinal section of one of the terminal electrodes, and Fig. 4 a diagram of the circuits to more clearly illustrate the working of the apparatus.
- 30 The cover A of the case, which may be of wood or any other non-conducting material, has an opening through which the top a of a battery-cell projects when the said cover is shut to close said case.
- 35 The cover a of the battery-cell referred to, and which may be of any well-known type—such as the Leclanché or bichromate—supports the positive and negative poles, herein shown as hollow posts a' a'', into which are inserted 40 the plugs a³ a⁴, when it is desired to place the battery in circuit.
- The cover A supports a vertical indicator or galvanometer, a⁵, having a case, a⁶, secured by screws a' to the cover A, the said indicator or galvanometer having a pointer or needle, a⁸, located outside the wire coils, and an armature, a⁹, mounted on the needle shaft or arbor a¹⁰ within the coils, the said indicator or galvanometer being included in circuit with the 45 battery.
- The armature a⁹, as herein shown, is composed of a star-shaped piece of soft iron which has been hardened and then charged in any well-known manner to form a permanent magnet, the points of the star forming three consecutive north and three consecutive south poles, as shown in Fig. 2.
- The shaft or arbor a¹⁰, as herein shown, has secured to it a weight, a¹², (see Fig. 2,) by means of which the needle a⁸ is restored to its 55 normal or vertical position when the current ceases to flow through the coils. One wire, b, leading to the indicator or galvanometer a⁵, is connected to the plug a⁴, (shown in Fig. 1,) the said plug being represented in Fig. 4 as 60 the negative pole of the battery, and the second wire, b', to one member, b², of a switch, the other member of which is a pivoted lever, b³, connected by a wire, b⁴, to a post, b⁵, of an ordinary telegraph-key, B, located upon the 65 cover of the box. A second post, b⁶, of the key B is joined to a pivoted lever, b⁷, forming one member of a switch, the co-operating member b⁸ of which is connected by wire b⁹ to the plug a³, (shown in Fig. 1,) and which is represented in Fig. 4 by the positive pole of the 70 battery.
- The indicator or galvanometer a⁵ is placed upon the cover A, so that its needle a⁸ will revolve in a plane at right angles to said cover. 75 The cover A also supports a galvanometer in circuit with the battery referred to, and is herein shown as marked to indicate points of the compass, said galvanometer having one of its wires, c', fastened to one member, c², of a switch, the co-operating member of which is the lever b³, and having its other wire, c³, joined to the wire b, connected with the plug a⁴, (shown in Fig. 1,) and which in Fig. 4 is represented by the negative pole of the battery.
- Secured to the cover A are two binding-posts, d d', the post d being connected by the wire d² to the wire b⁴, (see Fig. 4,) and the post d' by wire d³ to the switch member c² in the branch circuit.
- When it is desired to employ the apparatus to indicate the presence of mineral ores or deposits near the earth's surface, the lever b³ 95 will be turned, so as to co-operate with the member c², and thus place the galvanometer c 100

in circuit, the said galvanometer being substantially at right angles to the indicator or galvanometer a^5 , which circuit may be traced in Fig. 4 from the positive pole of the battery 5 by wire b^9 , lever b^1 , wire c^1 , to post b^6 , through the metallic frame of the key, lever b^{12} , and anvil b^{13} , (see Fig. 1,) to post b^5 , from thence by wire b^1 , lever b^3 , member c^2 , wire c^1 , through the galvanometer c , wires c^1 and b , to the negative pole of the battery. With the galvanometer c in circuit the apparatus is carried by the operator as he walks over the ground or territory to be examined, and the key B is worked to cause the galvanometer-needle to 15 be revolved.

By experiment it has been found that when the apparatus is brought in the vicinity of mineral ores or deposits the influence of said ores upon the galvanometer-needle is such as 20 to stop or retard to a considerable degree the revolution of said needle, thus indicating the presence of a mineral, notwithstanding the fact that the key is being constantly worked.

When it is desired to indicate the presence 25 of veins of mineral ores in a mine, shaft, or tunnel, it has been ascertained by experiment that the galvanometer c used for surface indications does not work advantageously, and for this purpose the indicator or galvanometer a^5 , placed at right angles to the galvanometer c , is employed.

When it is desired to employ the apparatus in a shaft or mine, the lever b^3 will be turned from its dotted to its full line position shown 35 in Fig. 4, thereby cutting out of circuit the galvanometer c and placing in circuit the indicator or galvanometer a^5 , said circuit being the same as that described for the galvanometer c to the lever b^3 , and said circuit is completed by switch member b^2 , line b^5 , galvanometer a^5 and wire b to the negative pole of the battery.

As the apparatus is carried down the shaft or mine to be examined, the operator varies his 45 position, so that the galvanometer may be turned through the different points of the compass, and the key B is constantly worked, thus causing the armature a^6 , and thereby the needle a^8 , to revolve; but when brought near a vein 50 of mineral ore the influence of said mineral ore upon the armature a^6 is such as to stop or to a great degree retard the revolution of the needle, the latter at such time pointing in the direction of the vein. The star-shaped armature 55 is caused to revolve by the current passing through the coils of the indicator or galvanometer a^5 as long as the said indicator or galvanometer is maintained in circuit with the battery and the apparatus is beyond the influence 60 of mineral deposits.

It has been found by experiment, when the apparatus is brought in the vicinity of small 65 deposits of ore, that normally the influence of the current upon the galvanometer-needle is greater than the influence of the said small mineral deposits, the needle under such cir-

cumstances being continuously revolved by the battery-current. Under these conditions it has been found necessary to employ a resistance, R , having one end connected to the positive pole of the battery by the wire b^9 , and being joined at its other end to the post b^6 of the key. This resistance R , when switched into circuit by turning the lever b^7 from its full to its dotted line position, (shown in Fig. 4,) reduces the current, so that it has but little effect upon the needle, it merely revolving the latter slowly and substantially uniformly, thus rendering the said needle sensitive to the action of very small deposits. This resistance R is also used in dry weather when it has been found that the needle is strongly affected by the current of the battery; but when the weather is cloudy and the air is charged with electricity, the resistance R will then be out of circuit, because the electricity of the air acts to somewhat counteract the battery-current.

When the apparatus is employed to indicate the presence of metallic substances under water or near the surface of land which is covered by water, or immediately beneath the bottom of a bay or harbor, the lever b^3 will be turned to occupy the position marked 2, between the switch members b^2 c^2 , and the terminal electrodes e e' will be placed in circuit 95 with the galvanometer c , the electrode e being connected by wire c^2 to the post d , and the electrode e' by wire e^2 to the post d' , said electrodes being separated by the insulating-block e' , the circuit-closer e^6 of the key B being 100 closed, as shown in Fig. 4, while the said electrodes are in use.

The electrodes e e' are each composed of a shell or case of copper or brass or other non-corroding metal and preferably of the shape indicated, said shell consisting of two parts, 105 3 4, screwed together, the part 4 being cored to receive within it a permanently-charged magnet, 5, herein shown as horseshoe in shape.

The wires e^2 e^3 are designed to be of such 110 length as will permit the electrodes e e' to drag on the bottom of the harbor or bay or other sheet of water, and the circuit of the electrodes will be closed when said electrodes come in contact with any metal substance, thus causing the galvanometer-needle to revolve, and said needle may be revolved even when said electrodes come in the immediate vicinity of metal substances without touching the same, the circuit being traced from the positive pole 115 of the battery by wire b^9 , lever b^1 , wire c^8 , post b^6 , circuit-closer e^6 , to post b^5 , wires b^1 d^2 , and c^2 , to electrode e , through the metal substance, electrode e' , wires e^1 , d^1 , and c' , through the galvanometer c , and thence to the negative 120 pole of the battery by wires c^3 and b .

We claim—

1. In an electrical indicating apparatus, a box or case, a battery, a substantially vertical indicator or galvanometer carried by said case 125 or box and provided with a pointer or needle, a pointer-shaft, and an armature mounted upon

- said shaft within the coils of the said indicator or galvanometer, combined with a key secured to the box and electrically connected with the battery and indicator or galvanometer, the 5 said pointer or needle being normally revolved by the battery current and being retarded or substantially stopped when brought in the presence of mineral deposits below the earth's surface, substantially as described.
- 10 2. In an electrical apparatus, a box or case, a battery, and a galvanometer carried by said box or case, combined with a key electrically connected with the said battery and galvanometer, and with a resistance to reduce the 15 strength of the battery current and enable the galvanometer-needle to be affected by small deposits of mineral near the earth's surface, and a switch to shunt the resistance out of circuit, substantially as described.
- 20 3. In an electrical indicating apparatus, a box or case, a battery, and an indicating device carried by the box or case, in circuit with the battery, combined with terminal electrodes
- e e', composed of a shell or case of non-corrod-
ing metal, and a permanently-charged magnet 25
contained therein in circuit with the indicat-
ing device, substantially as described.
4. The terminal electrodes consisting each
of a shell or case of non-corrod-
ing metal, and a permanently-charged magnet 30
located there-
in, substantially as described.
5. The terminal electrodes consisting each
of a shell or case composed of copper or brass
and cored to receive a permanent magnet, com-
bined with the permanently-charged magnet 35
inclosed within said shell or case, substantially
as described.

In testimony whereof we have signed our
names to this specification in the presence of
two subscribing witnesses.
